(57) **CLAIM**

What is claimed is the ornamental design for a polymeric plastic insert for a gift card container, as shown and described.

DESCRIPTION

FIG. 1 is an isometric exploded view showing a first embodiment of our new design for a polymeric plastic insert for a gift card container installed within a sheet metal gift card container, a gift card positioned for installation within a recess within the insert and a lid positioned for installation on the container;

FIG. 2 is an isometric top/end/side view of an injection-molded, first embodiment polymeric plastic insert for a gift card container;

FIG. 3 is an isometric bottom/end/side view thereof;

FIG. 4 is an elevational view of either side thereof;

FIG. 5 is an elevational view of either end thereof;

FIG. 6 is a top plan view thereof;

FIG. 7 is a bottom plan view thereof;

FIG. 8 is an isometric top/end/side view of a vacuum-formed, second embodiment polymeric plastic insert for a gift card container;

FIG. 9 is an isometric bottom/end/side view thereof;

FIG. 10 is an elevational view of either side thereof;

FIG. 11 is an elevational view of either end thereof;

FIG. 12 is a top plan view thereof;

FIG. 13 is a bottom plan view thereof; and,

FIG. 14 is an isometric exploded view showing a second embodiment of our new design for a polymeric plastic insert for a gift card container installed within a sheet metal gift card container, a gift card positioned for installation on the container.

The broken line in the drawings depict environmental subject matter only and form no party of the claimed design.
